REVERSIBLE ENVELOP.

(Application filed May 6, 1897.)

(No Model.)

FIG. 1.

FIG. 2.

FIG. 3.

FIG. 4.

UNITED STATES PATENT OFFICE.

EDWARD A. BURLINGAME, OF CLAYTON, NEW YORK.

REVERSIBLE ENVELOP.

SPECIFICATION forming part of Letters Patent No. 608,752, dated August 9, 1898.

Application filed May 6, 1897. Serial No. 635,327. (No model.)

To all whom it may concern.

Be it known that I, EDWARD A. BURLINGAME, of Clayton, in the county of Jefferson and State of New York, have invented certain new and useful Improvements in Envelops; and I do hereby declare the following to be a full, clear, and exact description of the invention, such as will enable others skilled in the art to which it appertains to make and use the same.

This invention relates to envelops, and especially to that class known as "return-envelops;" and it consists of a blank having flaps and wings adapted to be reversed or turned inside out to form a return-envelop, with printed matter primarily applied thereto on both sides of that part forming the face.

The invention further consists of a novel form of fastening device for sealing the envelop.

The invention further consists of the details of construction and arrangement of the several parts, which will be more fully herein-after described and claimed.

The object of the invention is to provide an envelop that can be easily reversed and is economical in that it replaces the additional envelop which is usually inclosed for return purposes, thereby saving the amount of paper and materially reducing the expense of return mail-matter.

In the accompanying drawings, Figure 1 is a plan view of a blank embodying the invention. Fig. 2 is a perspective view of the envelop shown arranged by the original sender. Fig. 3 is a perspective view of the envelop shown reversed and arranged by the return writer. Fig. 4 is an enlarged section on the line xx , Fig. 2. Fig. 5 is a perspective view looking toward the rear of the envelop and showing the latter partially folded. Fig. 6 is a perspective view of the improved form of fastening for the envelop.

Referring to the drawings, wherein similar numerals of reference are employed to indicate corresponding parts in the several views, the numeral 1 designates a blank having a central rectangular body 2, which has imprinted on one side thereof a merchant's or manufacturer's advertisement, as shown in Fig. 2, and instructions, as at 3, to refold the envelop and return samples or other matter

in the same. On the reverse face is imprinted the name of the manufacturer or merchant, and also such other matter as is allowable. 55 Extending from the opposite long side of the said rectangular body are rectangular flaps 4, having outer flaps 5 extending longitudinally of the said flaps, and to the ends of the said body are attached triangular wings or 60 flaps 6, and at the points of intersection of the wings or flaps 6 and the flaps 4 with the body 1 small triangular folds 7 are situated and close inwardly to secure the corners and prevent exposure of the contents of the envelop at this point. At the outer end of one of the flaps 6 is a slot 8, and in the opposite flap 6, at its outer end, are two slots 9 and 10, the slot 10 being smaller than the slot 9, and over the said ends of the flaps 6 having the 70 slots therein reinforce-pieces 11 are mounted, and at other points in the body of the envelop the parts may be reinforced as often as necessary and desirable.

In folding the envelop when first sending 75 it out from the manufacturer or merchant it is arranged as shown in Fig. 2 and the flaps 4 are turned inward over the back of the body 2 and expose the customer's name and address. When the said flaps 4 are turned inwardly, the folds 5 are interlocked and extend in different directions. This is more clearly shown in Fig. 5, and it will be seen that the triangular intersecting folds 7 are also closed with the end flaps or wings 6 downwardly over 85 the rear of the flaps 4 and folds 5. When the envelop is returned by the customer or party to whom it has been sent by the merchant or manufacturer, the said folds and flaps are reversed and the inner part of the body, bearing 90 the name of the said manufacturer or dealer in the form of an address, is exposed.

A preferred form of fastener is employed in connection with the envelop heretofore set forth, and consists of a sheet-metal plate 12, 95 which is longitudinally slotted, as at 13, to form securing-arms 14 and 15, the latter arm being slightly bent at 16 to form a small shoulder and facilitate the proper mounting of the same in position, as will be presently set forth. 100 The upper end of the said plate 12 is rebent to form a fastening 17, and this rebent end engages the slot 9 in one of the flaps or wings 6. The arm 15 is passed through the smaller

slot 10, with the shoulder 16 then positioned up within the said slot and the arms arranged at a proper level for engagement with the opposite flap or wing 6. In sending the envelop 5 out the arm 15 is passed through the slot 8 in the wing or flap 6 opposite to that carrying the said fastener and pressed against the inner side of the said flap when folded, the arm 14 in this instance being on the outside. When the 10 parts are reversed, the arm 14 is passed through the slot 8 and the arm 15 is on the outside of the envelop, and by this means a double fastening is conveniently provided. The object of this construction of fastener is to make it applicable 15 for securing the opposite flaps 6 when they are reversed and to bring the arms 14 and 15 alternately in interior and exterior positions. The function of the fastener is to hold the flaps closed against the back of the 20 envelop, sufficient friction being instituted between the arms 14 and 15 and the slot 8 to prevent accidental disengagement, but permitting the said flaps to be easily opened by pulling the fastener longitudinally from 25 the said slot. The envelop as an entirety is adapted to be used in sending samples from a merchant, dealer, or manufacturer to a customer or other person, and the samples can be returned by the customer or other person 30 after a choice has been made by the same envelop used by the said manufacturer or merchant and with a consequent material reduction in the expense and also with advantage to both parties.

It is obviously apparent that many minor 35 changes in the details of construction and arrangement of the several parts might be made and substituted for those shown and described without in the least departing from the nature or spirit of the invention. 40

Having thus described the invention, what is claimed as new is—

A reversible envelop having a body with the return address printed on one side and a sending address applied to the opposite side 45 together with the sender's name and residence, and formed with integral side flaps having outer folding portions adapted to interlock with each other when the said side flaps are turned over the body, end flaps connected to the said body and the side flaps by triangular corner-folds which are bent upon each other and in part lie over the side flaps when the latter are closed against the body, one of the end folds by its outer end being 50 slotted and a fastener carried by the opposite end fold having a pair of legs adapted to alternately engage the slot in the opposite end fold when the parts of the envelop are reversed, substantially as described. 55 60

In testimony whereof I have signed this specification in the presence of two subscribing witnesses.

EDWARD A. BURLINGAME.
